United States Patent Office

Des. 221,979
Patented Sept. 21, 1971

221,979

CHAFING DISH

Alfred W. Madl, Glendale, Wis., assignor to John Oster
Manufacturing Co., Milwaukee, Wis.

Filed July 15, 1970, Ser. No. 23,957

Term of patent 14 years

Int. Cl. D7—02

U.S. Cl. D44—15

Fig. 1.

Fig. 2.

Fig. 3.

Fig. 4.

Fig. 5.

FIG. 1 is a perspective view of a chafing dish embodying my new design;

FIG. 2 is a side elevational view of FIG. 3 thereof;

FIG. 3 is a top plan view thereof;

FIG. 4 is a bottom plan view thereof; and

FIG. 5 is an exploded perspective view showing the cover, the cooking vessel, and the water tray thereof. I claim:

The ornamental design for a chafing dish, as shown.
